UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed October 8, 1926, Serial No. 140,365. Renewed May 23, 1930.

This invention relates to mining machines and more particularly, but not exclusively, to coal mining machines of the wheel mounted "universal" type adapted to operate from the mine trackway.

An object of this invention is to provide an improved mining machine of the wheel mounted "universal" type adapted to operate either as a vertical cutter or as a horizontal cutter. Another object of this invention is to provide an improved mining machine of the wheel mounted type having an adjustable cutter carrying head and improved and simplified mechanism for adjusting the head. Still another object of this invention is to provide an improved mining machine having an adjustable cutter carrying head and a pivoted cutter bar mounted thereon and swingable relative thereto and having improved and simplified mechanism for swinging the cutter bar about its pivot and for rotating the cutter carrying head. A still further object of this invention is to provide a wheel mounted mining machine having improved mechanism for driving the truck wheels. A still further object of this invention is to provide an improved, simplified, and exceedingly compact general arrangement of parts whereby the machine may be operated with facility and expeditiously in mines having narrow or low veins. These and other objects and advantages of this invention will, however, hereinafter more fully appear.

Generally stated, the invention consists of the novel devices and combinations of devices hereinafter clearly described and defined in the appended claims.

In the accompanying drawings I have shown for purposes of illustration one form which my invention may assume in practice.

In these drawings,

Fig. 1 is a side elevation of a mining machine constructed in accordance with an illustrative embodiment of the invention, the cutter carrying head being shown in shearing position as indicated in full lines and in horizontal cutting position as indicated in dotted lines.

Fig. 2 is a plan view of the machine shown in Fig. 1, the horizontal cutting position of the cutter carrying head being indicated by dotted lines.

Fig. 3 is a central longitudinally extending sectional view taken on line 3—3 of Fig. 1 and illustrating the driving connections for the cutting mechanism.

Fig. 4 is a central longitudinally extending sectional view taken on line 4—4 of Fig. 2, the cutter carrying head being adjusted in the dotted line position as shown in Fig. 2.

Fig. 5 is a detail perspective view of one of the cutter bar locking elements.

Fig. 6 is a detail sectional view illustrating the locking means for the cutter carrying head.

Fig. 7 is a detail sectional view taken on line 7—7 of Fig. 6.

Fig. 8 is a central longitudinally extending sectional view taken on line 8—8 of Fig. 2.

Fig. 9 is a transverse vertical sectional view taken on line 9—9 of Fig. 8.

Fig. 10 is a transverse vertical sectional view taken on the line 10—10 of Fig. 3 and illustrating the main power controlling clutch for the cutting mechanism.

Fig. 11 is a detail view partially in section illustrating a portion of the operating mechanism for the fast and slow speed clutches shown in Fig. 8.

Fig. 12 is a transverse horizontal sectional view, partially in elevation, taken on line 12—12 of Fig. 1.

Fig. 13 is a transverse vertical sectional view taken on line 13—13 of Fig. 12.

Fig. 14 is a detail view taken on line 14—14 of Fig. 2.

Fig. 15 is a transverse vertical sectional view taken on line 15—15 of Figs. 3 and 4, illustrating the cutter carrying head rotating mechanism.

Fig. 16 is a transverse vertical sectional view taken on line 16—16 of Fig. 1.

In this illustrative embodiment of the invention I have shown a coal mining machine generally designated 1, the machine being of the so-called "universal" type mounted on

wheels and operating from the mine track-way. The machine 1 generally comprises a cutter carrying head or frame section 2, a motor section 3, and a section 4 housing the transmission mechanism for swinging the cutter bar about its pivot, for rotating the cutter carrying head, and for propelling the truck along the mine trackway, these elements all being mounted on a wheeled truck frame generally designated 5. The sections 3 and 4 are rigidly secured together and to the truck frame. The wheeled truck frame 5 specifically comprises parallel longitudinally extending angle members 6 held in rigid spaced relation by means of cross plates 7 and an end frame 8. The motor frame section and the section 4 are rigidly bolted to the angle members 6. Secured to the cross plates 7 are angle members 9 having depending flanges to which the axle boxes 10 for the axles 11 of the truck wheels 12 are adjustably secured.

In specifically describing the cutting mechanism, which is substantially the same as that described in my copending application Ser. No. 619,839, filed Feb. 19, 1923, it will be noted that housed within the motor section 3 is a suitable driving motor 13, herein preferably of the usual reversible electric type, having a longitudinally extending horizontal armature shaft 14. As shown in Fig. 4, the forward end of the armature shaft 14 is journaled in a suitable ball bearing 15 carried by a detachable head member 16 suitably secured within the motor section 3. The forward end of the armature shaft 14 has secured thereto by a screw and key connection 17 a coupling member 18 having internal teeth 19 which cooperate with flutes 20 formed on the shaft 21 alined with the armature shaft. The forward end of the shaft 21 is journaled in a suitable ball bearing 22 carried by a cylindrical neck or supporting portion 23 alined with the motor axis and formed integral with the front motor head 24, the latter being rigidly secured to the forward end of the motor section 3 by means of usual bolts 25. The cylindrical portion 23 forms a bearing for the cutter carrying head 2 in a manner to be later described, the cutter head being rotatable relative to the frame section 3. Referring to Figs. 3 and 4, it will be observed that the shaft 21 has formed integral therewith at its forward end a clutch member 26 which is adapted to be connected by means of a shiftable clutch member 27 to a clutch member 28 secured to a shaft 29 alined with the shaft 21. As illustrated, the clutch member 26 is internally bored as at 30 to receive a ball bearing 31 within which and a bearing 32 carried by the frame section 2, the shaft 29 is journaled. The shiftable clutch member 27 is adapted to be actuated longitudinally by means of a shipper yoke 33

(see Fig. 10) in the form of a bell crank pivoted at 34 on the frame section 2. This bell crank is provided with arms 35 and 36 adapted to cooperate with the clutch member 27 and a bifurcated member 37, respectively. The bifurcated member 37 is adapted to engage a vertical pin 38 upon the arm 36 and is suitably carried by a cylindrical member 39 slidably mounted within a sleeve 40 disposed within a transversely disposed bore 41 formed in the side of the frame section 2. Moreover, the sleeve 40 has secured thereto by radially extending studs 42 an operating member or grasping portion 43 and one of the studs is provided with an inwardly projecting pin adapted to cooperate with a cam slot 45 formed within the member 39. Furthermore, the member 39 is provided with an upstanding portion 46 having secured thereto at its upper end at 47 a transversely disposed rod 48 which is in turn secured at its opposite end within a cylindrical member 49 similar to the member 39 and likewise provided with an operating portion 50 disposed at the opposite side of the machine frame from the portion 43, thus enabling the operator to actuate the clutch from either side of the machine by transposition of the pin carrying stud. Rotation of the handles 43 and 50 effects axial movement of the members 39 and 49 and the rod 48, consequently swinging the clutch shipper yoke about its pivot. As the above clutch operating mechanism is clearly described in my copending application Ser. No. 757,031, filed Dec. 19, 1924, further description of the same is herein deemed unnecessary.

As illustrated, the shaft 29 has formed thereon a bevel pinion 51 which meshes with a bevel gear 52 rotatable on an axis perpendicular to the axis of the armature shaft and journaled in suitable spaced alined ball bearings 53 suitably carried within the machine frame. The bevel gear 52 has preferably formed integral therewith a spur pinion 54 which meshes with a large spur gear 55. As clearly shown in Fig. 3, the gear 55 is provided with an annular sleeve 56 journaled on spaced alined bearings 57 surrounding and disposed coaxially with a stationary shaft or stud 58 threadedly connected at its opposite ends to the machine frame. As illustrated, the sleeve on the gear 55 is connected through a semi-permanent clutch connection 59 with the adjacent end of a similar sleeve 60 on a cutter chain driving sprocket 61, the ends of the sleeve 60 being similarly journaled on axially spaced ball bearings 62 surrounding the shaft 58. The bearings 62 are spaced from and located relative to the bearings 57 by a flange 63 on the shaft. Moreover, the sleeve on the gear 55 and an adjacent portion of the sleeve 60 are enclosed within an outside sleeve mem-

ber 64 suitably fixed to the frame. Disposed on the opposite side of the sprocket 61 from the bearing sleeve 64 is a bearing sleeve 65 fixed to the shaft 58 by a pin and slot connection 66. As shown, surrounding the sleeves 64 and 65 are bearing sleeves 67 on which an elongated plane cutter bar 68 is pivotally mounted. A cutter bit carrying cutter chain 69 is adapted to be circulated about the outer edges of the cutter bar 68 by the cutter chain sprocket 61. From the foregoing description it will be obvious that the cutter chain may be actuated by the motor or remain idle while the motor continuously operates.

Improved means are provided for locking the cutter bar 68 to the cutter head in its different adjusted positions. This locking means specifically comprises a projecting boss 70 formed integrally with the cutter bar 68 and grooved as at 71 to overlie and, if necessary, to be supported on a radial flange portion 72 formed integral with the cutter carrying head 2, the boss 70 being adapted to engage the sides of the flange 72 to maintain the cutter bar in the desired plane of swing. As clearly shown in Fig. 3, disposed in the bore 73 formed in the boss 70 are axially movable clamp members 74, 75 having formed on their inner surfaces serrations 76 which are adapted to grip the opposite surfaces of the flange 72. Threadedly connected to the clamping members 74 and 75 is a bolt 77 having right and left hand threads. It will be evident that upon rotation of the bolt 77 the serrations on the clamping members 74 and 75 are forced into engagement with the flange 72, thereby rigidly locking the cutter bar in position.

In specifically describing the improved transmission mechanism housed within the frame section 4, it will herein be observed that the rear end of the armature shaft 14 of the driving motor (see Fig. 8) has suitably secured thereto a spur pinion 80 which is adapted to drive the truck wheel driving mechanism, the mechanism for swinging the cutter bar, and the mechanism for rotating the cutter carrying head and including transmission gearing and controlling clutches substantially similar to those described in my copending application Ser. No. 757,031 mentioned above, at a slow speed in one direction or at a fast speed in the opposite direction without reversing the motor. In specifically describing the fast speed transmission mechanism, it will be noted that the pinion 80 meshes with a spur gear 81 suitably journaled within bearings 82 carried by the frame section 4. The gear 81 has secured thereto and rotatable therewith a spur pinion 83 which meshes with a larger internal gear 84. The hub 85 of the gear 84 is herein also journaled on a suitable bearing sleeve 86 carried by a sleeve clutch

member 87 keyed as at 88 to the longitudinally disposed horizontal main transmission shaft 89, the latter being journaled at its opposite ends in bearings 90 and 91 suitably carried within the frame section 4. Moreover, it will be noted that the clutch member 87 carries a series of friction clutch discs 92 which are interleaved with a corresponding series of clutch discs 93 carried by the sleeve of the internal gear 84. As shown, the sleeve of this internal gear is also provided with a plurality of radially located longitudinally extending slots 94 receiving radial fingers 95 formed on an interlocking member 96 keyed to the hub of a pinion 97 freely rotatable on the shaft 89. Interposed between these fingers 95 are friction clutch operating fingers 97a carried by an axially movable cylindrical plane clutch operating member 98 disposed coaxially with and encircling the hub of the member 96. These fingers 97a extend longitudinally into contact with the adjacent end clutch disc of the clutch 92, 93. As shown, the rear end of the shaft 89 has secured thereto by a key 99 a spur pinion 100 which meshes with a spur gear 101 journaled within suitable bearings 102 carried by the frame section 4. The spur gear 101 has secured thereto and rotatable therewith a spur pinion 103 which meshes with a larger internal gear 104 keyed as at 105 to a longitudinally extending horizontal shaft 106, the latter being disposed coaxially with the transmission shaft 89. The shaft 106 is journaled in spaced aligned roller bearings 107 and 108 suitably carried by the machine frame. It will thus be evident that rotation of the armature shaft 14 will be transmitted to the pinion 80, gear 81, pinion 83, internal gear 84, friction clutch discs 92, 93, clutch member 87, shaft 89, pinion 100, gear 101, pinion 103, internal gear 104, and the shaft 106 to rotate the latter at a predetermined high or fast speed whenever the clutch controlling member 98 is operated to connect the clutches 92 and 93. It will further be noted that this speed may be lowered at will by slipping the friction disc 92, 93 of the clutch.

Now referring specifically to the slow speed transmission, it will be noted that when the clutch operating member 98 is in its inoperative position and the clutch 92, 93 is released, power will still be transmitted through the interlocking member 96 and the pinion 97 which is freely rotatable on the shaft 89. This pinion 97 in turn meshes with a gear 109 disposed coaxially with the gear 81 and this gear has secured thereto and rotatable therewith a pinion 110 which meshes with a spur gear 111 disposed coaxially with and rotatable on the shaft 89. This gear 111 has secured thereto and rotatable therewith a spur pinion 112 which meshes with a spur gear 113 arranged coaxially with

- the gear 109 and this gear has secured thereto and rotatable therewith a spur pinion 114. The spur pinion 114 meshes with an internal gear 115 substantially similar to the internal gear 84. The internal gear 115 also houses 5 a friction clutch substantially similar to the clutch heretofore described in connection with the clutch disc 92, 93 and this clutch includes a series of interleaved clutch discs 116, 117 certain of which are carried on a clutch member 118, keyed as at 119 to the shaft 89, while others are carried by a sleeve formed on the internal gear 115. A clutch retaining member 120 is provided keyed as 10 at 121 to the hub of the spur pinion 100 and this clutch member in this instance has no interlocking function and is only a disc retaining member. An axially movable cylindrical plane clutch operating member 122 surrounds the hub of the disc retaining member 120 and is provided with longitudinally extending fingers 123 which are adapted to engage the adjacent end disc of the clutch 116, 117. As a result of this slow speed 15 mechanism above described, although the clutch 92, 93 is disconnected, rotation will constantly be imparted through the pinion 97, gear 109, pinion 110, gear 111, pinion 112, gear 113, pinion 114, internal gear 115, clutch disc 116, 117, clutch member 118, pinion 100, gear 101, pinion 103, internal gear 104, to the shaft 106 so that when the clutch 116, 117 is connected, the shaft 106 will be rotated at a slow speed in an opposite 20 direction from the fast speed previously described. Here it will also be evident that by slipping the friction discs 116, 117 of the slow speed clutch, this speed may be reduced at will.
- 25 The clutch operating members 98 and 122 may be operated to alternatively apply their respective clutches by means of suitable shifter mechanism which is clearly described in my copending application Ser. No. 757,031 mentioned above. This shifter mechanism comprises, as clearly shown in Figs. 8, 9 and 11, pivoted clutch shifter members 124 and 125 each provided at one end with suitable rollers 126 adapted to engage the plane surfaces of the clutch operating members 98 and 122 respectively. The outer ends of these shippers are also provided with rectangular portions 127 and 128 having arcuate engaging surfaces and these 30 portions register with slots 129 and 130 respectively formed in slidably engageable parallel rods 131 and 132 suitably guided in the machine frame at their opposite ends. These actuating rods are grooved or cut 35 away at 133 and 134 to permit longitudinal relative movement therebetween and are provided at their rear ends with semicircular screw portions 135 and 136 which have threads 137 and 138 of opposite pitch and 40 are adapted to engage a nut 139 having in-
- ternal threads of opposite pitch which engage the threads on the members. The nut 139 has secured thereto a grasping or operating portion 140 conveniently located at the rear end of the machine frame. It will be 45 observed that by rotating the handle 140 and consequently the threaded nut 139 engaging the threads formed on the rods 131 and 132 will cause the latter to simultaneously move in opposite directions and causing one of the 50 friction mechanisms to be released while the other is applied, thereby preventing the simultaneous application of two speeds, i. e. the fast and slow speeds.
- 55 As clearly shown in Fig. 12 the rear end 50 of the shaft 106 is fluted or grooved at 141 with which internal teeth 142 formed on the slidable clutch member 143 are adapted to cooperate. As shown, the teeth 142 are also adapted to engage flutes or grooves 144 55 formed on the forward end of a shaft 145 arranged coaxially with the shaft 106. It will therefore be evident that the shafts 106 and 145 may be connected or disconnected at will. The shaft 145 is fluted or 60 grooved at its rear end as at 146, and cooperating with these flutes are internal teeth 147 formed on a hollow shaft 148 journaled at its opposite ends in spaced alined ball bearings 149 suitably carried by a clutch 65 housing 150, the latter being suitably rigidly secured to the truck frame 5. The shaft 148 has secured thereto at its rear end by a key 151, a bevel gear 152 which meshes with reverse bevels 153, 154 freely rotatable upon 70 bearing sleeves 155 carried by a transversely disposed horizontal truck driving shaft 156, the latter being journaled at its opposite ends in suitable ball bearings 157 suitably carried by the gear housing 150. As illustrated, the hubs of the gears 153, 154 are disposed adjacent one another and have formed thereon gear clutch teeth 158, 159 adapted to be selectively connected by a shiftable clutch member 160 with a clutch member 161 herein preferably formed integral with the shaft 156 intermediate the ends thereof. A shifter yoke 162 engages the clutch member 160 and is secured to a vertical shaft 163 75 suitably journaled on the gear housing 150. This shaft has secured thereto at its upper end an operating lever 164, the latter being adapted to be held in its different adjusted positions by means of a latch 165 pivoted on the lever 164 and engageable with a notched 80 segment 166 suitably secured to the gear housing. It will thus be evident that by selectively throwing the clutch member 160 in opposite directions into operative engagement with either of the clutch members 158, 159, the shaft 156 may be driven in opposite 85 directions by the gear 152 at either a fast or a slow speed.
- 90 As clearly shown in Figs. 12 and 13, the shaft 156 has secured thereto at one end 95

thereof by a screw and key connection 167 a sprocket 168. The sprocket 168 is connected by an endless chain connection 169 and a sprocket 170 keyed to one end of a horizontal transversely disposed shaft 171 disposed parallel with and below the shaft 156. The shaft 171 is suitably journaled in the bearing sleeve 172 carried within an adjustable bracket 173 suitably secured to the truck frame. It will also be observed that secured to the end of the shaft 171 opposite from the sprocket 170 is a sprocket 174 which is connected, as clearly shown in Figs. 1 and 2, by an endless chain connection 175 to a sprocket 176 suitably rigidly secured to the rear axle of the truck. The bracket 173 may be adjusted relative to the truck frame to vary the tension of the drive chains. The front and rear truck axles are connected in driving relation by means of a chain and sprocket connection 177. From the foregoing description it will be obvious that when the shafts 106 and 145 are connected in driving relation and when one or the other of the gears 158 and 159 are connected to the shaft 156, the truck wheels may be driven at fast or slow speeds and in opposite directions.

In specifically describing the improved mechanism for swinging the cutter bar 68 about its pivot and for rotating the cutter carrying head 2, it will be observed that rotatably mounted on the rear end of the shaft 106 (see Fig. 8) is a chain sprocket 180. This sprocket has formed thereon external clutch teeth 181 which are adapted to cooperate with internal clutch teeth 182 formed on the slideable clutch member 143. When the clutch member 143 is slid forwardly out of engagement with the shaft 145, the teeth 182 engage the teeth 181 of the chain sprocket, thereby connecting the latter in driving relation with the shaft 106. Cooperating with the chain sprocket 180 is a flexible transmission chain 183 herein preferably of the loose link type and this chain cooperates with the cutter bar and the cutter carrying head in an improved and simplified manner and herein constitutes the final transmission element for effecting head rotation and bar swing. The intermediate portion of this chain 183 passes over the upper surface of the chain sprocket 180 downwardly from opposite sides thereof and around guide sprockets or sheaves 184 and 185 rotatably mounted on brackets 186 suitably rigidly secured to the rear cross plate 7 of the truck frame. The chain passes around the guide sheaves 184 and 185 and then extends forwardly through the truck frame, the end portions of the chain crossing beneath the middle of the machine as clearly shown in Fig. 2, and passing around angularly disposed guide sprockets or sheaves 187, 188 suitably rotatably mounted on brackets 189 secured as by bolts 190 to

the frame section 3. The chain then passes around the guide sheaves 187 and 188 upward in opposite directions around the top of circumferentially extending guiding grooves 191 and 192 formed on a cylindrical member 193 forming a part of the cutter carrying head 2, and this member is rotatably mounted on spaced alined ball bearings 194 carried by the cylindrical neck portion 23 heretofore described. The chain 183 extends from the guiding grooves 191 and 192 around guide sprockets or sheaves 195 and 196 rotatable on axes extending longitudinally of the machine and hence around laterally located guide sprockets or sheaves 197 and 198 carried by the cutter carrying head and rotatable on axes extending transversely of the machine. The chain 183 then extends from the guide sheaves 196, 197 forwardly around the arcuate portion 199 of the cutter carrying head 2 adjacent the flange 72 and the free ends of the chain carry hooks 200 which are connected to projecting lugs 201 formed on the clamping member 75 as is clearly shown in Figs. 1 and 5.

Improved means is provided for locking the cutter carrying head against rotation and such means comprises a locking pin 202 (see Figs. 4, 6 and 7) rotatably mounted within a bore 203 formed within a boss 204 herein preferably formed integral with the front motor head 24. As shown, the boss 204 is grooved to overlie a radially extending flange 205 formed integral with the cutter carrying head 2 to maintain the cutter carrying head in the desired plane of movement. The rotatable locking pin 202 is provided with a removable flange 206 at its forward end while the rear end of the pin is flanged as at 207 and these flanges prevent longitudinal separation of the pin from the boss 204 while permitting free rotation thereof. Herein it will also be noted that the pin 202 is slotted transversely intermediate its ends as at 208 in such manner as to form a locking portion having a concave face and adapted to be received in any one of a plurality of corresponding cut-away portions 209 on the flange 205 when the pin is suitably turned, these cut-away portions 209 herein being so disposed on the head as to enable the bar to be locked in horizontal or vertical positions. Moreover, it will be noted that the pin 202 has keyed thereto at 210 an operating rod 211 which extends rearwardly of the machine and has secured thereto at its rear end an operating handle (not shown), this handle being conveniently located adjacent the clutch controlling handle 140.

From the foregoing description it will be obvious that when the sprocket 180 is rotated in one direction, it being understood that the cutter carrying head is locked in

position by the pin 202 and that the locking clamp 74, 75 is released, tension is applied to one portion of the chain while the other portion thereof is paid out and the cutter bar 5 may consequently be swung in one direction about its pivot at a predetermined speed, while if the sprocket 180 is rotated in an opposite direction the chain is drawn in in an opposite manner and the cutter bar 10 may consequently be swung about its pivot in the opposite direction at a different speed. It will also be noted that when the cutter bar 68 is rigidly locked to the cutter carrying head and that when the locking pin 202 15 is released, the chain 183 may be drawn in by the sprocket 180 to bodily rotate the cutter carrying head in one direction at a predetermined speed, and that when the other portion of the chain 183 is drawn in, 20 the cutter carrying head may be rotated in an opposite direction at a higher speed, the pull of the chain on the laterally located guide sprockets 197 and 198 effecting rotation of the head. 25 Suitably secured to the rear truck axle is a frictional braking device 212 (see Fig. 2) and this braking device is adapted to be operated through suitable connections 213, 214, the rear end of the latter connection 30 being connected to an operating lever 215. This frictional braking device is adapted to control rotation of the truck wheels when the mining apparatus is moving over an inclined trackway and is also adapted to 35 lock the truck wheels against rotation during the cutting operation.

In the operation of my improved mining machine it will be noted that when the latter is moving rapidly about the mine, the clutch teeth 159 and 161 are connected by the 40 clutch member 160 connecting the bevel gear 154 in driving relation with the shaft 156, it being understood that the motor is running and the fast speed clutch 92, 93 is applied and consequently the shaft 145 is rotating at a high speed. When it is desired to 45 drive the mining machine rearwardly along the trackway at a high speed, the bevel gear 154 is disconnected from the shaft 156 and the bevel gear 153 is connected to the shaft by means of its controlling clutch and consequently the truck wheels are driven in opposite directions. When the machine is disposed adjacent the working face and if it 55 is desired to make a horizontal or arc-wall cut, the operator disconnects the bevel gear 154 from the shaft 156 and slides the clutch member 143 forwardly, disconnecting the shafts 106 and 145 and connecting the 60 sprocket 180 to the shaft 106. The cutter carrying head is locked in position by the locking pin 202 with the cutter bar disposed in its horizontal or undercutting position as indicated by dotted lines in Fig. 2, 65 and the locking means 74, 75 is released.

The desired portion of the chain 183 is then drawn in by the sprocket 180, it being understood that the fast speed clutch 92, 93 is still applied and consequently the cutter bar is swung laterally at a high speed to a point adjacent the right hand rib, the cutter bar thereafter being locked in position. The fast feed clutch 92, 93 is then released and the clutch member 143 is slid rearwardly connecting the shafts 106, 145 in driving relation. The clutch teeth 158, 161 are then connected by the clutch member 160, thereby connecting the bevel gear 153 to the shaft 156, and upon application of the slow speed clutch 116, 117, the cutter bar is sumped into the coal at a cutting speed, the machine moving bodily along the trackway at that time. At the completion of the sumping cut, the slow speed clutch 116, 117 is released and the clutch member 143 is shifted forwardly, disconnecting the shaft 145 from the shaft 106 and connecting the sprocket 180 to the latter. The friction braking device 212 is then applied, holding the truck wheels against rotation. The slow speed clutch 116, 117 is then applied and the cutter bar is swung about its pivot at a cutting speed, it being understood that the cutter bar lock is released at that time. After the swinging cut is completed the brake 212 is released, the slow speed clutch 116, 117 is released, and the sprocket 180 is disconnected from the shaft 106, the latter and the shaft 145 then being connected in driving relation. The clutch teeth 159 and 161 are then connected to the clutch member 160 thereby connecting the bevel gear 154 to the shaft 156. Upon re-application of the slow speed clutch 116, 117, the cutter bar is withdrawn from the coal at a cutting speed, the mining machine moving rearwardly along the trackway at that time. If it is desired to make a shear or vertical cut, the sprocket 180 is connected to the shaft 106 and the shafts 145 and 106 are disconnected. The locking pin 202 is then released and upon application of one of the speed controlling clutches, the cutter carrying head is rotated at the desired speed to the position shown in Fig. 1, the cutter carrying head thereafter being locked in position. The locking means for the cutter bar is then released and the cutter bar is swung upwardly at a fast speed to the upper dotted line position shown in Fig. 1. The bevel gear 153 is then connected to the shaft 156, the sprocket 180 released from the shaft 106 and the shafts 145 and 106 connected in driving relation by the clutch member 143. Upon application of the slow speed clutch, 125 the cutter bar is sumped into the coal at a cutting speed. The cutter bar is then swung downwardly at a cutting speed to the bottom of the mine and the bar is thereafter withdrawn at a cutting speed from the coal in a 130

manner substantially similar to that hereto-
for described in regard to the horizontal cut.
The cutter bar is thereafter swung upwardly
to the full line position shown in Fig. 1
5 and the machine is moved rearwardly at a
high speed along the trackway and away
from the working face. These and other
operations and advantages of my improved
10 coal mining machine will be clearly appar-
ent to those skilled in this art.

As a result of this invention it will be
noted that improved and simplified mech-
anism is provided for rotating the cutter
carrying head and for swinging the pivoted
15 cutter bar wherein a single final transmis-
sion chain is utilized. It will further be
noted that by utilizing the single final
transmission chain for rotating the cutter
carrying head and for swinging the cutter
20 bar all complicated mechanism is eliminated,
the machine being of exceedingly simple
and rugged character especially adapted to
the severe mining conditions encountered.

While I have in this application speci-
25 cally described one form which my invention
may assume in practice, it will be under-
stood that this form of the same is shown
for purposes of illustration and that the in-
vention may be modified and embodied in
30 various other forms without departing
from its spirit or the scope of the appended
claims.

What I claim as new and desire to secure
by Letters Patent is:

35 1. In a mining machine, the combination
of a body, a cutter carrying head rotatably
mounted on said body and having a kerf
cutting cutter bar mounted thereon, a motor
in said body, and means driven by said motor
40 for rotating said head to change the plane of
operation of said bar comprising a rotatable
member and a flexible transmission element
cooperating therewith and operatively con-
nected to said head.

45 2. In a mining machine, the combination
of a body, a cutter carrying head rotatably
mounted on said body and having a pivoted
cutter mounted thereon and swingable rela-
tive thereto, a motor in said body, and means
50 driven by said motor for rotating said head
comprising a rotatable member and a single
flexible transmission element having an inter-
mediate portion engaging said member
and end portions connected to said head.

55 3. In a mining machine, the combination
of a body, a cutter carrying head rotatably
mounted on said body about a substantially
horizontal axis and having a kerf cutting
cutter bar mounted thereon, a motor in said
60 body, and means driven by said motor for
rotating said head to change the plane of
operation of said bar comprising a rotatable
member and a flexible transmission element
cooperating therewith and operatively con-
65 nected to said head.

4. In a mining machine, the combination
of a body, a cutter carrying head rotatably
mounted on said body about a substantially
horizontal axis and having a pivoted cutter
70 mounted thereon and swingable relative
thereto, a motor in said body, and means
driven by said motor for rotating said head
comprising a rotatable member and a single
flexible transmission element having an in-
75 termediate portion engaging said member
and end portions connected to said head.

5. In a mining machine, the combination
of a body, a cutter carrying head rotatably
mounted on said body and having a pivoted
cutter mounted thereon and swingable rela-
tive thereto, a motor in said body, and means
80 driven by said motor for rotating said head
comprising a rotatable member, a flex-
ible transmission element cooperating there-
with and operatively connected to said head
and constituting the final transmission ele-
85 ment for effecting head rotation, and means
for rotating said member at different speeds
to effect rotation of said head at correspond-
ing speeds.

6. In a mining machine, the combination
of a body, a cutter carrying head rotatably
mounted on said body and having a pivoted
cutter mounted thereon and swingable rela-
tive thereto, a motor in said body, and means
90 driven by said motor for rotating said head
comprising a rotatable member, a flexible
element cooperating therewith and oper-
atively connected to said head and constitut-
ing the final transmission element for effect-
95 ing head rotation, and means for rotating
said member at different speeds and in oppo-
site directions for effecting rotation of said
head at corresponding speeds in opposite
100 directions.

7. In a mining machine, the combination
of a truck supported body, a cutter carrying
head rotatably mounted on said body and
having a pivoted cutter mounted thereon and
swingable relative thereto, a motor in
110 said body, and means driven by said motor
for rotating said head comprising a rotatable
member, a single flexible transmission ele-
ment having an intermediate portion engag-
ing said member and end portions connected
115 to said head, and means for rotating said
member at different speeds.

8. In a mining machine, the combination
of a truck supported body, a cutter carrying
head rotatably mounted on said body, a
motor in said body and having a pivoted
cutter mounted thereon and swingable rela-
tive thereto, and means driven by said motor
120 for rotating said head comprising a rotatable
member, a single flexible transmission ele-
ment having an intermediate portion engag-
ing said member and end portions connected
to said head, and means for rotating said
125

member at different speeds and in opposite directions.

9. In a mining machine, the combination of a truck supported body, a cutter carrying head rotatably mounted on said body, a motor in said body and having a pivoted cutter mounted thereon and swingable relative thereto, and means driven by said motor for rotating said head at a slow speed in one direction and at a higher speed in the opposite direction comprising a rotatable member and a flexible element cooperating therewith, said element being operatively connected to said head and constituting the final transmission element for effecting head rotation.

10. In a mining machine, the combination of a truck supported body, a cutter carrying head rotatably mounted on said body, a motor in said body and having a pivoted cutter mounted thereon and swingable relative thereto, and means driven by said motor for rotating said head at a slow speed in one direction and at a higher speed in the opposite direction comprising a rotatable member and a single flexible transmission element having an intermediate portion engaging said member and end portions connected to said head.

11. In a mining machine, the combination of a truck supported body, a cutter carrying head rotatably mounted on said body, a motor in said body and having a pivoted cutter mounted thereon and swingable relative thereto, and means driven by said motor for rotating said head at different speeds in opposite directions comprising a rotatable member and a flexible transmission element cooperating therewith, said element being operatively connected to said head and constituting the final transmission element for effecting head rotation.

12. In a mining machine, the combination of a truck supported body, a cutter carrying head rotatably mounted on said body, a motor in said body and having a pivoted cutter mounted thereon and swingable relative thereto, and means driven by said motor for rotating said head at different speeds in opposite directions comprising a rotatable member and a single flexible transmission element having an intermediate portion engaging said member and end portions connected to said head.

13. In a mining machine, the combination of a truck supported body, a cutter carrying head rotatably mounted on said body about a horizontal axis and having a pivoted cutter mounted thereon and swingable relative thereto, a motor in said body, and means driven by said motor for rotating said head about its axis comprising a member rotatable at a slow speed in one direction and at a higher speed in the opposite direction and a flexible transmission ele-

ment cooperating therewith and operatively connected to said head.

14. In a mining machine, the combination of a truck supported body, a cutter carrying head rotatably mounted on said body, a motor in said body and having a pivoted cutter mounted thereon and swingable relative thereto, and means driven by said motor for rotating said head comprising a member rotatable at a slow speed in one direction and at a higher speed in the opposite direction and a single flexible transmission element having an intermediate portion engaging said member and end portions connected to said head.

15. In a mining machine, the combination of a truck supported body, a cutter carrying head rotatably mounted on said body and having a pivoted cutter mounted thereon and swingable relative thereto, a horizontal motor in said body having its axis extending longitudinally of the machine, and means driven from the rear end of said motor for rotating said head comprising a rotatable member and a flexible transmission element cooperating therewith.

16. In a mining machine, the combination of a truck supported body, a cutter carrying head rotatably mounted on said body and having a pivoted cutter mounted thereon and swingable relative thereto, a horizontal motor in said body having its axis extending longitudinally of the machine, and means driven from the rear end of said motor for rotating said head comprising a rotatable member and a single flexible transmission element having an intermediate portion engaging said member and end portions connected to said head.

17. In a mining machine, the combination of a truck supported body, a cutter carrying head rotatably mounted on said body and having a pivoted cutter mounted thereon and swingable relative thereto, a horizontal motor in said body having its axis extending longitudinally of the machine, and means driven by said motor for rotating said head at different speeds in opposite directions comprising a rotatable member and a flexible transmission element cooperating therewith.

18. In a mining machine, the combination of a truck supported body, a cutter carrying head rotatably mounted on said body and having a pivoted cutter mounted thereon and swingable relative thereto, a horizontal motor in said body having its axis extending longitudinally of the machine, and means driven by said motor for rotating said head at different speeds in opposite directions comprising a rotatable member and a single flexible transmission element having an intermediate portion engaging said member and end portions connected to said head.

19. In a mining machine, the combination of a truck supported body, a cutter carrying head rotatably mounted on said body about a horizontal axis and having a pivoted cutter mounted thereon and swingable relative thereto, a motor in said body, mechanism driven from one end of said motor for actuating the cutter, and means driven from the opposite end of said motor for rotating said head about its axis comprising a rotatable member and a flexible transmission element cooperating therewith and operatively connected to said head. 5
20. In a mining machine, the combination of a truck supported body, a cutter carrying head rotatably mounted on said body and having a pivoted cutter mounted thereon and swingable relative thereto, a motor in said body, mechanism driven from one end of said motor for actuating the cutter, and means driven from the opposite end of said motor for rotating said head comprising a rotatable member and a single flexible transmission element having an intermediate portion engaging said member and end portions connected to said head. 10
21. In a mining machine, the combination of a truck supported body, a cutter carrying head rotatably mounted on said body about a horizontal axis and having a pivoted cutter mounted thereon and swingable relative thereto, a motor in said body, mechanism driven from one end of said motor for actuating the cutter, and means driven from the opposite end of said motor for rotating said head about its axis at different speeds in opposite directions comprising a rotatable member and a flexible transmission element cooperating therewith and operatively connected to said head. 15
22. In a mining machine, the combination of a truck supported body, a cutter carrying head rotatably mounted on said body and having a pivoted cutter mounted thereon and swingable relative thereto, a motor in said body, mechanism driven from one end of said motor for actuating the cutter, and means driven from the opposite end of said motor for rotating said head about its axis at different speeds in opposite directions comprising a rotatable member and a single flexible transmission element having an intermediate portion engaging said member and end portions connected to said head. 20
23. In a mining machine, the combination of a truck supported body, a cutter carrying head rotatably mounted on said body and having a pivoted cutter mounted thereon and swingable relative thereto, a horizontal motor in said body having its axis extending longitudinally of the machine, means driven from the forward end of said motor for actuating said cutter, and means driven from the rear end of said motor for rotating said head comprising a rotatable 25
- member and a flexible transmission element cooperating therewith. 70
24. In a mining machine, the combination of a truck supported body, a cutter carrying head rotatably mounted on said body and having a pivoted cutter mounted thereon and swingable relative thereto, a horizontal motor in said body having its axis extending longitudinally of the machine, means driven from the forward end of said motor for actuating said cutter, and means driven from the rear end of said motor for rotating said head comprising a rotatable member and a single flexible transmission element having an intermediate portion engaging said member and end portions connected to said head. 75
25. In a mining machine, the combination of a body, a cutter carrying head rotatably mounted on said body, a motor in said body and having a pivoted cutter mounted thereon and swingable relative thereto, and means driven by said motor for rotating said head comprising a rotatable member, a flexible transmission element cooperating therewith, and laterally located abutments on said head with which said element cooperates. 80
26. In a mining machine, the combination of a body, a cutter carrying head rotatably mounted on said body and having a pivoted cutter mounted thereon and swingable relative thereto, a motor in said body, and means driven by said motor for rotating said head comprising a rotatable member, a flexible transmission element cooperating therewith, and laterally located guide sheaves on said head with which said element cooperates. 85
27. In a mining machine, the combination of a truck supported body, a cutter carrying head rotatably mounted thereon about a substantially horizontal axis and having a neck portion, said neck portion having guiding grooves thereon, a motor in said body, and means driven by said motor for rotating said head comprising a rotatable member and a flexible transmission element cooperating with said member and guided in said grooves. 90
28. In a mining machine, the combination of a truck supported body, a cutter carrying head rotatably mounted thereon about a substantially horizontal axis and having a neck portion, said neck portion having guiding grooves thereon, a motor in said body, and means driven by said motor for rotating said head comprising a rotatable member and a single flexible transmission element having an intermediate portion engaging said member and end portions guided in said grooves and connected to said head. 95
29. In a mining machine, the combination of a truck supported body, a cutter carrying head rotatably mounted thereon about a 100

substantially horizontal axis and having a neck portion, said neck portion having guiding grooves thereon, a motor in said body, and means driven by said motor for rotating said head at different speeds in opposite directions comprising a rotatable member and a flexible transmission element cooperating with said member and guided in said grooves.

10 30. In a mining machine, the combination of a truck supported body, a cutter carrying head rotatably mounted thereon about a substantially horizontal axis and having a neck portion, said neck portion having guiding grooves thereon, a motor in said body, and means driven by said motor for rotating said head at different speeds in opposite directions comprising a rotatable member and a single flexible transmission element having an intermediate portion engaging said member and end portions guided in said grooves and connected to said head.

15 31. In a mining machine, the combination of a truck supported body, a cutter carrying head rotatably mounted thereon about a substantially horizontal axis and having a neck portion, said neck portion having guiding grooves thereon, a motor in said body, and means driven by said motor for rotating said head comprising a member rotatable at a slow speed in one direction and at a higher speed in the opposite direction and a flexible transmission element cooperating with said member and guided in said grooves.

20 35 32. In a mining machine, the combination of a truck supported body, a cutter carrying head rotatably mounted thereon about a substantially horizontal axis and having a neck portion, said neck portion having guiding grooves thereon, a motor in said body, and means driven by said motor for rotating said head comprising a member rotatable at a slow speed in one direction and at a higher speed in the opposite direction and a single flexible transmission element having an intermediate portion engaging said member and end portions guided in said grooves and connected to said head.

25 30 33. In a mining machine, the combination of a body, a head rotatably mounted on said body and carrying a pivotally mounted cutter bar swingable relative thereto, a motor in said body, and means driven by said motor for rotating said head and for swinging said cutter bar relative to said head comprising a rotatable member and a flexible transmission element cooperating therewith.

30 35 34. In a mining machine, the combination of a body, a head rotatably mounted on said body and carrying a pivotally mounted cutter bar swingable relative thereto, a motor in said body, and means driven by said motor for rotating said head and swinging said cutter bar relative to said head comprising a rotatable member and a single

flexible transmission element having an intermediate portion engaging said member and end portions connected to said bar.

35 35. In a mining machine, the combination of a body, a head rotatably mounted on said body and carrying a pivotally mounted cutter bar swingable relative thereto, a motor in said body, and means driven by said motor for rotating said head and swinging said cutter bar relative to said head comprising a flexible transmission element having end portions connected to said bar and means for drawing in said portions.

40 36. In a mining machine, the combination of a body, a head rotatably mounted on said body and carrying a pivotally mounted cutter bar swingable relative thereto, a motor in said body, and means driven by said motor for rotating said head and swinging said cutter bar relative to said head comprising a flexible transmission element having end portions connected to said bar and means for drawing in said portions at different speeds.

45 37. In a mining machine, the combination of a truck supported body, a head rotatably mounted on said body, and carrying a pivotally mounted cutter bar swingable relative thereto, a motor in said body, and means driven by said motor for rotating said head and swinging said cutter bar relative to said head comprising a rotatable member, a single flexible transmission element having an intermediate portion engaging said member and end portions connected to said bar, and means for rotating said member at different speeds.

50 38. In a mining machine, the combination of a truck supported body, a head rotatably mounted on said body and carrying a pivotally mounted cutter bar swingable relative thereto, a motor in said body, and means driven by said motor for rotating said head and swinging said cutter bar relative to said head comprising a rotatable member, a single flexible transmission element having an intermediate portion engaging said member and end portions connected to said bar, and means for rotating said member at different speeds and in opposite directions.

55 39. In a mining machine, the combination of a truck supported body, a head rotatably mounted on said body and carrying a pivotally mounted cutter bar swingable relative thereto, a motor in said body, and means driven by said motor for rotating said head and swinging said cutter bar relative to said head comprising a rotatable member and a flexible transmission element cooperating therewith, and means for rotating said member at a slow speed in one direction and at a fast speed in the opposite direction.

60 40. In a mining machine, the combina- 130

tion of a truck supported body, a head rotatably mounted on said body and carrying a pivotally mounted cutter bar swingable relative thereto, a motor in said body, and means driven by said motor for rotating said head and swinging said cutter bar relative to said head comprising a rotatable member, a single flexible transmission element having an intermediate portion engaging said member and end portions connected to said bar, and means for rotating said member at a slow speed in one direction and at a fast speed in the opposite direction.

41. In a mining machine, the combination of a truck supported body, a head rotatably mounted on said body and carrying a pivotally mounted cutter bar swingable relative thereto, a motor in said body, and means driven by said motor for rotating said head and swinging said cutter bar relative to said head comprising a rotatable member and a single flexible transmission element cooperating therewith, said element having an end thereof connected to said bar and an intermediate portion engaging said head.

42. In a mining machine, the combination of a truck supported body, a head rotatably mounted on said body and carrying a pivotally mounted cutter bar swingable relative thereto, a motor in said body, and means driven by said motor for rotating said head and swinging said cutter bar relative to said head comprising a rotatable member and a single transmission flexible element cooperating therewith, said element having its ends connected to the bar and intermediate portions engaging said head.

43. In a mining machine, the combination of a truck supported body, a head rotatably mounted on said body and carrying a pivotally mounted cutter bar swingable relative thereto, a motor in said body, and means driven by said motor for rotating said head and swinging said cutter bar relative to said head comprising a rotatable member and a single flexible transmission element having an intermediate portion engaging said member and end portions connected to said head and cutter bar.

44. In a mining machine, the combination of a body, a head rotatably mounted on said body and carrying a pivotally mounted cutter bar swingable relative thereto, a motor in said body, and means driven by said motor for rotating said head at different speeds and swinging said cutter bar relative to said head comprising a rotatable member and a flexible transmission element cooperating therewith.

45. In a mining machine, the combination of a body, a head rotatably mounted on said body and carrying a pivotally mounted cutter bar swingable relative thereto, a motor in said body, and means driven by said motor

for rotating said head at different speeds and swinging said cutter bar relative to said head comprising a rotatable member and a single flexible transmission element cooperating therewith, said flexible element having end portions connected to said bar and intermediate portions engaging said head.

46. In a mining machine, the combination of a truck supported body, a head rotatably mounted on said body and carrying a pivotally mounted cutter bar swingable relative thereto, a motor in said body, and means driven by said motor for rotating said head at different speeds in opposite directions and for swinging the said cutter bar relative to said head comprising a rotatable member and a flexible transmission element cooperating therewith.

47. In a mining machine, the combination of a truck supported body, a head rotatably mounted on said body and carrying a pivotally mounted cutter bar swingable relative thereto, a motor in said body, and means driven by said motor for rotating said head at different speeds in opposite directions and for swinging said cutter bar relative to said head comprising a rotatable member and a single transmission flexible element cooperating therewith, said flexible element having its end portions connected to said bar and intermediate portions engaging said head.

48. In a mining machine, the combination with a truck supported body, a head rotatably mounted on said body and carrying a pivotally mounted cutter bar swingable relative thereto, a motor in said body, and means driven by said motor for rotating said head at a slow speed in one direction and at a higher speed in the opposite direction and for swinging said cutter bar relative to said head comprising a rotatable member and a flexible transmission element cooperating therewith.

49. In a mining machine, the combination with a truck supported body, a head rotatably mounted on said body and carrying a pivotally mounted cutter bar swingable relative thereto, a motor in said body, and means driven by said motor for rotating said head at a slow speed in one direction and at a higher speed in the opposite direction and for swinging said cutter bar relative to said head comprising a rotatable member and a single flexible transmission element cooperating therewith, said flexible element having its end portions connected to said bar and intermediate portions engaging said head.

50. In a mining machine, the combination of a truck supported body, a head rotatably mounted on said body and carrying a pivotally mounted cutter bar swingable relative thereto, a motor in said body, and means driven by said motor for rotating said head and for swinging said cutter bar at different speeds relative to said head comprising a

rotatable member and a flexible transmission element cooperating therewith.

51. In a mining machine, the combination of a truck supported body, a head rotatably mounted on said body and carrying a pivotally mounted cutter bar swingable relative thereto, a motor in said body, and means driven by said motor for rotating said head and for swinging said cutter bar at different speeds relative to said head comprising a rotatable member and a single flexible transmission element cooperating therewith, said flexible element having its end portions connected to said bar and intermediate portions engaging said head.
52. In a mining machine, the combination of a body, a head rotatably mounted on said body and carrying a pivotally mounted cutter bar swingable relative thereto, a motor in said body, and means driven by said motor for rotating said head and for swinging said cutter bar relative to said head at different speeds in opposite directions comprising a rotatable member and a flexible transmission element cooperating therewith.

53. In a mining machine, the combination of a body, a head rotatably mounted on said body and carrying a pivotally mounted cutter bar, swingable relative thereto, a motor in said body, and means driven by said motor for rotating said head and for swinging said cutter bar at different speeds in opposite directions relative to said head comprising a rotatable member and a single flexible transmission element cooperating therewith, said flexible element having its end portions connected to said bar and intermediate portions engaging said head.

54. In a mining machine, the combination of a truck supported body, a head rotatably mounted on said body and carrying a pivotally mounted cutter bar swingable relative thereto, a motor in said body, and means driven by said motor for rotating said head and for swinging said cutter bar at a cutting speed in one direction and at a higher speed in the opposite direction relative to said head comprising a rotatable member and a flexible transmission element cooperating therewith.

55. In a mining machine, the combination of a truck supported body, a head rotatably mounted on said body and carrying a pivotally mounted cutter bar swingable relative thereto, a motor in said body, and means driven by said motor for rotating said head and for swinging said cutter bar at a cutting speed in one direction and at a higher speed in the opposite direction relative to said head comprising a rotatable member and a single flexible transmission element cooperating therewith, said flexible element having its end portions connected to said

bar and intermediate portions engaging said head.

56. In a mining machine, the combination of a truck supported body, a head rotatably mounted on said body and carrying a pivotally mounted cutter bar swingable relative thereto, a motor in said body, and means driven by said motor for rotating said head and for swinging said cutter bar at different speeds relative to said head comprising a rotatable member and a single flexible transmission element having an intermediate portion engaging said member and having its end portions connected to said bar.

57. In a mining machine, the combination of a truck supported body, a head rotatably mounted on said body and carrying a pivotally mounted cutter bar swingable relative thereto, a motor in said body, and means driven by said motor for rotating said head and for swinging said cutter bar at different speeds in opposite directions relative to said head comprising a rotatable member and a single flexible transmission element having an intermediate portion engaging said member and end portions connected to said bar.

58. In a mining machine, the combination of a truck supported body, a head rotatably mounted on said body and carrying a pivotally mounted cutter bar swingable relative thereto, a motor in said body, and means driven by said motor for rotating said head and for swinging said cutter bar at a cutting speed in one direction and at a higher speed in the opposite direction relative to said head comprising a rotatable member and a single flexible transmission element having an intermediate portion engaging said member and end portions connected to said bar.

59. In a mining machine, the combination of a truck supported body, a head rotatably mounted on said body and carrying a pivotally mounted cutter bar swingable relative thereto, a motor in said body, and means driven by said motor for both rotating said head and swinging said cutter bar at different speeds relative to said head comprising a rotatable member and a single flexible transmission element cooperating therewith and having its end portions connected to said bar and intermediate portions engaging said head.

60. In a mining machine, the combination of a truck supported body, a head rotatably mounted on said body and carrying a pivotally mounted cutter bar swingable relative thereto, a motor in said body, and means driven by said motor for both rotating said head and swinging said cutter bar relative to said head at different speeds in opposite directions comprising a rotatable member and a single flexible transmission element cooperating therewith and having its end

portions connected to said bar and intermediate portions engaging said head.

61. In a mining machine, the combination of a truck supported body, a head rotatably mounted on said body and carrying a pivotally mounted cutter bar swingable relative thereto, a motor in said body, and means driven by said motor for both rotating said head and swinging said cutter bar relative to said head at a slow speed in one direction and at a higher speed in the opposite direction comprising a rotatable member and a single flexible transmission element cooperating therewith and having its end portions connected to said bar and intermediate portions engaging said head.

62. In a mining machine, the combination of a truck supported body, a cutter carrying head rotatably mounted thereon and having a pivoted cutter mounted thereon and swingable relative thereto, a motor in said body, means for driving the wheels of said truck, means for rotating said head including a rotatable member and a flexible transmission element cooperating therewith, and means for alternatively connecting said truck wheel driving means and said head rotating means in driving relation with said motor.

63. In a mining machine, the combination of a truck supported body, a head rotatably mounted on said body and carrying a pivotally mounted cutter bar swingable relative thereto, a motor in said body, means driven by said motor for driving the wheels of said truck, and means driven by said motor for rotating said head and for swinging said cutter bar relative to said head comprising a single flexible transmission element and a rotating member cooperating therewith.

64. In a mining machine, the combination of a truck supported body, a head rotatably mounted on said body and carrying a pivotally mounted cutter bar swingable relative thereto, mechanism driven from the forward end of said motor for actuating the cutters on said bar, mechanism driven from the rear end of said motor for driving the wheels of said truck, and means driven by the rear end of said motor for rotating said head and for swinging said cutter bar relative to said head comprising a flexible transmission element and a rotatable member cooperating therewith.

65. In a mining machine, a cutter carrying head having a cutter bar pivotally mounted thereon, and means for locking said bar to said head in different adjusted positions comprising a clamping device carried by

said bar and means for adjusting said device.

66. In a mining machine, a cutter carrying head having a cutter bar pivotally mounted thereon, and means for locking said bar to said head in different adjusted positions comprising serrated clamping members car-

ried by said bar and means for adjusting said clamping members.

67. In a mining machine, a cutter carrying head having a flange thereon, a cutter bar pivotally mounted on said head, means for locking said bar to said head in different adjusted positions comprising a clamping device carried by said bar and engaging said flange, and means for adjusting said clamping device.

68. In a mining machine, a cutter carrying head having a flange thereon, a cutter bar pivotally mounted on said head, and means for locking said cutter bar to said head in different adjusted positions comprising serrated clamping members engaging the opposite sides of said flange, and means for adjusting said members.

69. In a mining machine, the combination of a body, a head rotatably mounted thereon and carrying a pivotally mounted cutter swingable relative thereto, and means for rotating said head and swinging said cutter bar relative to said head including a common flexible transmission element.

70. In a mining machine, the combination of a truck supported body, a head rotatably mounted on said body and carrying a pivotally mounted cutter bar swingable relative thereto, a motor in said body, and means driven by said motor for rotating said head and swinging said cutter bar relative to said head including a common flexible transmission element.

71. In a mining machine, the combination of a body, a head rotatably mounted thereon about a substantially horizontal axis and carrying a pivotally mounted cutter bar swingable relative thereto, and means for rotating said head and swinging said cutter bar at different speeds relative to said head including a common flexible transmission element.

72. In a mining machine, the combination of a body, a cutter carrying head rotatably mounted on said body and having cutting mechanism mounted thereon including a pivoted cutter bar swingable relative thereto, and carrying orbitally moving cutting elements, a horizontal motor in said body having its axis extending longitudinally of the machine, driving mechanism for actuating the cutting elements of said cutting mechanism in their orbits driven from one end of said motor, and mechanism driven from the opposite end of said motor for swinging said bar about its pivot relative to said head in any adjusted position of said head about its axis.

73. In a mining machine, the combination of a body, a cutter carrying head rotatably mounted on said body and having cutting mechanism mounted thereon including a pivoted cutter bar swingable relative thereto, a horizontal motor in said body hav-

ing its axis extending longitudinally of the machine, driving mechanism for actuating said cutting mechanism driven from the front end of said motor, and mechanism 5 driven from the rear end of said motor for swinging said bar about its pivot relative to said head in any adjusted position of said head about its axis.

74. In a mining machine, the combination 10 of a body, a cutter carrying head rotatably mounted on said body and having a pivoted cutter bar mounted thereon, a motor in said body, and mechanism driven by said motor for swinging said bar about its pivot in 15 any adjusted position of said head about its axis comprising a rotatable operating member, and flexible swinging means operatively connected to said bar and having an intermediate portion engaging said member.

75. In a mining machine, the combination 20 of a body, a cutter carrying head rotatably mounted on said body and having a pivoted cutter bar mounted thereon and swingable relative thereto and carrying orbitally moving cutting elements, a horizontal motor in 25 said body having its axis extending longitudinally of the machine, mechanism driven from the forward end of said motor for actuating the cutting elements in their orbits 30 on said cutter bar, and mechanism driven from the rear end of said motor for effecting rotation of said head and for swinging said bar about its pivot relative to said head in any adjusted position of said head about its 35 axis.

76. In a mining machine, the combination 40 of a body, a cutter carrying head rotatably mounted on said body and having a pivoted cutter bar mounted thereon, a horizontal motor in said body having its axis extending longitudinally of the machine, mechanism 45 driven from the forward end of said motor for actuating said cutter bar, and mechanism driven from the rear end of said 50 motor for effecting rotation of said head and for swinging said bar about its pivot in any adjusted position of said head about its axis comprising a rotatable operating member and flexible swinging means operatively connected to said head and cutter bar and having an intermediate portion engaging said member.

77. In a mining machine, the combination 55 of a body, kerf cutting mechanism carried thereby including a pivoted cutter bar swingable in a vertical plane to cut a vertical kerf, a motor, and means driven by said motor for swinging said bar about its pivot comprising a rotatable operating member 60 and flexible swinging means having end portions operatively connected to said bar and an intermediate portion engaging said rotatable member.

78. In a mining machine, the combination 65 of a body, kerf cutting mechanism carried

thereby including a pivoted cutter bar swingable in a vertical plane to cut a vertical kerf, a motor, and constantly operative means driven by said motor for swinging said bar about its pivot in opposite directions comprising a rotatable operating member and flexible swinging means having end portions connected to said bar and an intermediate portion engaging said rotatable member. 70

79. In a mining machine, the combination 75 of a body, a cutter carrying head rotatably mounted on said body and having a pivoted cutter bar mounted thereon, a motor, and mechanism driven by said motor for swinging said bar about its pivot relative to said head while said head is held against rotation and for rotating said head when said bar is held against swinging movement relative to said head including a rotating member 80 and flexible bar swinging means operatively connected to said head and bar and having an intermediate portion engaging said rotatable member.

80. In a mining machine, the combination 85 of a body, a cutter carrying head rotatably mounted on said body and having a pivoted cutter bar mounted thereon, a motor, mechanism driven by said motor for swinging said bar about its pivot relative to said head while said head is held against rotation and for rotating said head when said bar is held against swinging movement relative to said head including a rotating member and flexible bar swinging means operatively connected to said head and bar and having an intermediate portion engaging said rotatable member, and means operable at will for holding said head stationary or said bar against such swinging movement during 90 either of said operations. 100

81. In a mining machine, the combination 105 of a body, a cutter carrying head rotatably mounted on the forward end of said body about a horizontal axis and having cutting mechanism thereon including a pivoted cutter bar swingable relative thereto and carrying orbitally moving cutting elements, a horizontal motor having its axis extending longitudinally of the machine, mechanism 110 driven from one end of said motor for actuating the cutting elements of said cutting mechanism in their orbits, and mechanism driven from the opposite end of said motor for effecting rotation of said head to change the plane of operation of said bar and for swinging said bar about its pivot relative to said head in any adjusted position of said head about its axis. 115

82. In a mining machine, the combination 120 of a body, a cutter carrying head rotatably mounted on the forward end of said body about a horizontal axis and having cutting mechanism thereon including a pivoted cutter bar swingable relative thereto, a hori- 125

zontal motor having its axis extending longitudinally of the machine, mechanism driven from the front end of said motor for actuating said cutting mechanism, and mechanism driven from the rear end of said motor for effecting rotation of said head to change the plane of operation of said bar and for swinging said bar about its pivot relative to said head in any adjusted position of said head about its axis.

83. In a mining machine, a wheeled support, a machine body thereon, a cutter carrying head rotatably mounted on said body and having cutting mechanism thereon including a pivoted cutter bar swingable relative thereto and carrying orbitally moving cutting elements, a horizontal motor having its axis extending longitudinally of said body, mechanism driven from one end of said motor for actuating the cutting elements of said cutting mechanism in their orbits, mechanism driven from the opposite end of said motor for effecting rotation of said head and for swinging said bar about its pivot relative to said head in any adjusted position of said head about its axis, and mechanism driven from the last mentioned end of said motor for driving the wheels of said support.

84. In a mining machine, a wheeled support, a machine body thereon, a cutter carrying head rotatably mounted on said body and having cutting mechanism thereon including a pivoted cutter bar swingable relative thereto and carrying orbitally moving cutting elements, a horizontal motor having its axis extending longitudinally of said body, mechanism driven from the front end of said motor for actuating the cutting elements of said cutting mechanism in their orbits, mechanism driven from the rear end of said motor for effecting rotation of said head and for swinging said bar about its pivot relative to said head in any adjusted position of said head about its axis, and mechanism driven from the last mentioned end of said motor for driving the wheels of said support.

85. In a mining machine, the combination of a body, a head rotatably mounted on said body and carrying a pivoted cutter bar swingable relative thereto, a motor in said body, and means driven by said motor for effecting rotation of said head about its axis comprising a rotatable member and a flexible transmission element cooperating with said member and engaging said head at points offset from its axis of rotation.

86. In a mining machine, the combination of a body, a head rotatably mounted on said body and carrying a pivoted cutter bar swingable relative thereto, a motor in said body, and means driven by said motor for effecting rotation of said head about its axis comprising a rotatable oper-

ating member and flexible head rotating means including a flexible transmission element cooperating with said member and having portions engaging said head at diametrically opposite points offset from its axis of rotation.

87. In a mining machine, the combination of a body, a cutter carrying head rotatably mounted on said body, a motor in said body, and means driven by said motor for effecting rotation of said head about its axis comprising a rotatable member and a flexible transmission element cooperating with said member and engaging said head at points offset from its axis of rotation and having portions partially encircling said axis.

88. In a mining machine, the combination of a body, a cutter carrying head rotatably mounted on said body, a motor in said body, and means driven by said motor for effecting rotation of said head about its axis comprising a rotatable operating member and flexible rotating means including a flexible transmission element cooperating with said member and having portions engaging said head at diametrically opposite points offset from its axis of rotation and portions partially encircling said axis.

89. In a mining machine, a wheeled support, a machine body thereon, cutting mechanism including a cutter carrying head rotatably mounted in said body and having a pivoted cutter bar mounted thereon, a motor, mechanism driven by said motor for actuating said cutting mechanism, mechanism driven by said motor for effecting rotation of said head and for swinging said cutter bar about its pivot in any adjusted position of said head, mechanism driven by said motor for driving the wheels of said support, and controlling mechanism for said head rotating and bar swinging and said support wheel driving mechanisms preventing connection of said head rotating and bar swinging mechanism and said wheel driving mechanism in driving relation with said motor except alternatively.

90. In a mining machine, a wheeled support, a machine body thereon, cutting mechanism including a cutter carrying head rotatably mounted on said body and having a pivoted cutter bar mounted thereon and carrying orbitally moving cutting elements, a horizontal motor having its axis extending longitudinally of the machine, driving connections for actuating the cutting elements of said cutting mechanism in their orbits driven from one end of said motor, mechanism driven from the opposite end of said motor for effecting rotation of said head and for swinging said cutter bar about its pivot in any adjusted position of said head, and mechanism driven by said motor for driving the wheels of said support, said bar

swinging and head rotating mechanism and said wheel driving mechanism being only alternatively connectible in driving relation with said motor.

5. 91. In a mining machine, the combination of a body, a head rotatably mounted thereon and carrying a pivotally mounted cutter swingable relative thereto, and means for rotating said head and swinging said cutter bar including a common flexible element operatively connected to said head and cutter bar and constituting the final transmission element for effecting head rotation and swinging of said bar.

15. 92. In a mining machine, the combination of a truck supported body, a head rotatably mounted on said body and carrying a pivotally mounted cutter bar swingable relative thereto, a motor in said body, and means driven by said motor for rotating said head and swinging said cutter bar including a common flexible element operatively connected to said head and cutter bar and constituting the final transmission element for effecting head rotation and swinging of said bar.

30. 93. In a mining machine, the combination of a body, a head rotatably mounted thereon about a substantially horizontal axis and carrying a pivotally mounted cutter bar swingable relative thereto, and means for rotating said head and swinging said cutter bar at different speeds including a common flexible element operatively connected to said head and cutter bar and constituting the final transmission element for effecting head rotation and swinging of said bar.

40. 94. In a mining machine, a cutter support, a cutter bar pivotally mounted on said support, and means for locking said bar to said support in different adjusted positions comprising a clamping device movable about the bar pivot upon swinging movement of said bar and engageable with an element of said support, and means for adjusting said device.

50. 95. In a mining machine, a cutter support, a cutter bar pivotally mounted on said support for swinging in a plane, and means for locking said bar against such swinging movement relative to said support comprising a clamping device carried by one of said elements and engageable with the other element, and means for adjusting said device.

55. 96. In a mining machine, a cutter support, a cutter bar pivotally mounted on said support, and means for locking said bar to said support in different adjusted positions comprising a clamping device carried by said bar and means for adjusting said device.

60. 97. In a mining machine, the combination of a body, a cutter carrying head rotatably mounted about a longitudinal axis on said body, a motor, and means driven by said motor for effecting rotation of said head

about its axis comprising a rotatable power operated member and a flexible transmission element engaging said member and engaging said head at points offset from its axis of rotation and partially encircling said head axis.

70. 98. In a mining machine, the combination of a body, a cutter carrying head rotatably mounted on said body, a motor, and means driven by said motor for effecting rotation of said head about its axis comprising a rotatable power operated member arranged in axial alinement with the head axis and a flexible transmission element engaging said member and engaging said head at points offset from its axis of rotation and partially encircling said head axis.

75. 99. In a mining machine, the combination with a body, a cutter carrying head rotatably mounted on said body about a substantially horizontal axis and having a neck portion, said neck portion having a guiding groove thereon, a motor, and means driven by said motor for rotating said head comprising a rotatable driving member and a flexible transmission element engaging said driving member and said head and having a portion guided in the groove on said neck portion.

80. 100. In a mining machine, the combination with a body, a cutter carrying head rotatably mounted on said body about a horizontal axis and carrying a pivoted cutter bar swingable relative thereto, a motor, and mechanism driven by said motor for swinging said bar relative to said head comprising a rotatable driving member arranged in axial alinement with the head axis and a flexible transmission element engaging said driving member and connected to said bar.

85. 101. In a mining machine, a portable frame, a motor thereon having its power shaft extending longitudinally of the machine, kerf cutting mechanism carried by said frame including a head rotatable about a longitudinal axis coincident with the motor axis and a kerf cutter pivotally mounted on said head, a plural predetermined speed transmission mechanism driven by said motor, and mechanism driven through said plural speed transmission mechanism and receiving power therefrom selectively at any of the predetermined terminal speeds thereof for rotating said head and for swinging said kerf cutter about its pivot both at different speeds.

100. 102. In a mining machine, a portable frame, a motor thereon having its power shaft extending longitudinally of the machine, kerf cutting mechanism carried by said frame including a head rotatable about a longitudinal axis coincident with the motor axis and a kerf cutter pivotally mounted on said head, a plural predetermined speed transmission mechanism driven by said motor

5 tor, mechanism driven through said plural speed transmission mechanism and receiving power therefrom selectively at any of the predetermined terminal speeds thereof for rotating said head and for swinging said kerf cutter about its pivot, both at different speeds, and mechanism driven through said transmission mechanism for propelling the machine at different speeds.

10 103. In a mining machine, a portable frame, a motor thereon having its power shaft extending longitudinally of the machine, kerf cutting mechanism carried by said frame adjacent the forward end thereof and including a head rotatable about a longitudinal axis and a kerf cutter pivotally mounted on said head, driving connections between the forward end of said motor and said cutting mechanism, a plural predetermined speed transmission mechanism driven by said motor, and mechanism driven through said plural speed transmission mechanism and receiving power therefrom selectively at any of the predetermined terminal speeds thereof for rotating said head and for swinging said kerf cutter about its pivot both at different speeds, said head rotating mechanism being driven from the rear end of said motor.

15 104. In a mining machine, a portable frame, a motor thereon having its axis extending longitudinally of the machine, kerf cutting mechanism carried by said frame including a head rotatable about a longitudinal axis coincident with the motor axis and a kerf cutter pivotally mounted on said head, a variable speed transmission mechanism driven by said motor and controllable, though the motor speed remains constant, to provide different driving speeds, mechanism driven through said variable speed transmission mechanism for rotating said head and for swinging said kerf cutter about its pivot both at variable speeds, and mechanism driven through said variable speed transmission mechanism for propelling the machine at variable speeds.

20 105. In a mining machine, a portable frame, a motor thereon having its axis extending longitudinally of the machine, kerf cutting mechanism carried by said frame including a head rotatable about a longitudinal axis coincident with the motor axis and a kerf cutter pivotally mounted on said head, a plural speed transmission mechanism driven by said motor and including a fast speed gear train and a slow speed gear train, mechanism driven selectively through either of said gear trains for rotating said head and for swinging said kerf cutter about its pivot, both at different speeds, and mechanism driven selectively through either of said gear trains for propelling the machine at different speeds.

25 106. In a mining machine, a portable

frame, a motor thereon having its power shaft extending longitudinally of the machine, kerf cutting mechanism carried by said frame adjacent the forward end thereof and including a head rotatable about a longitudinal axis and a kerf cutter pivotally mounted on said head, a plural speed transmission mechanism driven from the rear end of said motor and including a frictionally controlled fast speed gear train and a frictionally controlled slow speed gear train, mechanism driven through said gear trains for rotating said head and for swinging said kerf cutter about its pivot both at different speeds, and mechanism driven through said gear trains for propelling the machine at different speeds.

30 107. In a mining machine, a portable frame, a motor thereon having its power shaft extending longitudinally of the machine, kerf cutting mechanism carried by said frame adjacent the forward end thereof and including a head rotatable about a longitudinal axis and a kerf cutter pivotally mounted on said head, a plural speed transmission mechanism driven from the rear end of said motor and including a fast speed gear train and a slow speed gear train and friction controlling clutches one individual to each gear train, mechanism driven through said gear trains for rotating said head and for swinging said kerf cutter about its pivot both at different speeds, and mechanism driven through said gear trains for propelling the machine at different speeds.

35 108. In a mining apparatus, the combination of a body, a cutter head rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a rotatable member, and a flexible transmission element connected between said member and said head and cutter bar, and means for holding said head against rotation during bar swing.

40 109. In a mining apparatus, the combination of a body, a cutter head rotatably mounted on said body and having a pivoted cutter bar mounted thereon, a motor in said body, and mechanism driven by said motor for rotating said head and for swinging said cutter bar about its pivot relative to said head in any adjusted position of the latter about its axis comprising a rotatable member, a flexible transmission element connected between said member and said head and cutter bar, and means for holding said cutter bar against swinging movement relative to said head during head rotation.

45 110. In a mining apparatus, a wheeled truck adapted to run along a mine trackway, cutting mechanism including a frame mount-

ed on and rigidly and permanently secured to said truck and a kerf cutter pivotally mounted on said frame for swinging movement relative thereto and carrying orbitally 5 moving cutting elements, a motor carried by said frame and having its power shaft extending longitudinally of the apparatus and driving from one end the cutting elements of said cutting mechanism in their orbits, a 10 plural speed transmission mechanism carried by said frame and operatively connected to the opposite end of said power shaft and having its terminal element rotatable on an axis extending longitudinally of the apparatus, constantly operative means connected 15 to said kerf cutter and driven by said terminal element of said plural speed transmission mechanism for positively swinging said kerf cutter about its pivot in opposite directions, and mechanism driven through said transmission mechanism for driving the truck wheels to propel the apparatus bodily along the mine trackway to effect opposite rectilinear movements of said kerf cutter at 20 25 a cutting speed.

111. In a mining apparatus, a wheeled truck adapted to run along a mine trackway, cutting mechanism including a frame mounted on and rigidly and permanently secured 30 to said truck and a kerf cutter at the forward end of said apparatus and pivotally mounted on said frame for swinging movement relatively thereto, a motor carried by said frame and having its power shaft extending longitudinally of the apparatus and driving from the front end of said cutting mechanism, a plural speed transmission mechanism carried by said frame and operatively connected to the rear end of said 35 40 power shaft and having its terminal element rotatable on an axis extending longitudinally of the apparatus, constantly operative means connected to said kerf cutter and driven by said terminal element of said plural speed transmission mechanism for positively swinging said kerf cutter about its pivot in opposite directions, and mechanism driven through said transmission mechanism for driving the truck wheels to propel 45 50 the apparatus bodily along the mine trackway to effect opposite rectilinear movements of said kerf cutter at a cutting speed.

In testimony whereof I affix my signature.

MORRIS F. HOLMES.

CERTIFICATE OF CORRECTION.

Patent No. 1,813,803.

Granted July 7, 1931, to

MORRIS P. HOLMES.

It is hereby certified that error appears in the printed specification of the above numbered patent requiring correction as follows: Page 4, line 9, for the word "innerleaved" read interleaved; page 6, line 4, for the misspelled word "portion" read portion; page 7, lines 123 to 125, claim 8, strike out the words "and having a pivoted cutter mounted thereon and swingable relative thereto" and insert the same to follow the word "body" in line 122 of same claim; page 8, lines 6 to 8, 19 to 21, 32 to 34, 45 to 47, and 71 to 73, claims 9, 10, 11, 12 and 14, respectively, strike out the words "and having a pivoted cutter mounted thereon and swingable relative thereto" and insert the same to follow the word "body" lines 5, 18, 31, 44 and 70, in the respective claims; page 13, line 89, claim 69, for the misspelled word "realtive" read relative; and that the said Letters Patent should be read with these corrections therein that the same may conform to the record of the case in the Patent Office.

Signed and sealed this 3rd day of November, A. D. 1931.

**M. J. Moore,
Acting Commissioner of Patents.**
